LIQUID DISTRIBUTING SYSTEM

Francis J. Wiegand, Ridgewood, William T. Stark, Pompton Lakes, and Mark R. Rowe, Teaneck, N. J., assignors to Curtiss-Wright Corporation, a corporation of Delaware

Original application February 23, 1944, Serial No. 523,770, now Patent No. 2,430,264, dated November 4, 1947. Divided and this application October 7, 1947, Serial No. 778,418

6 Claims. (Cl. 137—608)

1

This invention is a division of application Serial Number 523,770, filed February 23, 1944, now Patent Number 2,430,264, issued November 4, 1947, and relates to liquid distributing systems.

An object of this invention comprises the provision of a liquid distributing system which automatically maintains an equal division of flow between a plurality of passages. A still further object of this invention comprises the provision of a liquid distributing system which automatically maintains said division of flow between the plurality of passages not only with changes in the total magnitude of the flow but also with changes in the relative elevation of said passages.

The invention is described in connection with a fuel distributing system for a multi-cylinder internal combustion engine. As will appear, however, the invention herein claimed is not so limited and instead is of general application.

Other objects of the invention will become apparent upon reading the annexed detailed description in connection with the drawing in which:

Figures 1 and 2 are schematic rear end and side views, respectively, illustrating the invention applied to a radial cylinder internal combustion engine, and

Figure 3 is a detailed section view of one of the discharge nozzles.

Referring to the drawing, a conventional radial cylinder aircraft engine 10 is provided with radially disposed cylinders 11 having intake and exhaust valves 12 and 13, respectively. A carburetor or other fuel metering device 14, to which fuel is supplied under pressure, is supported on the engine or section 16. A carburetor adapter or conduit section 18 establishes communication between the carburetor and the intake of a conventional engine driven supercharger 20, which in turn discharges the combustion air into an annular manifold 22 from whence it is distributed to the various engine cylinders through their intake pipes 24. The structure so far described is quite conventional.

The fuel metering device 14 may comprise any suitable mechanism to which fuel is supplied under pressure and in which the fuel is metered and delivered under pressure, for example, in accordance with the total air flow as in the fuel metering device disclosed in Patent No. 2,165,447 to K. Browne. The metered fuel is delivered to a fuel reservoir or fuel distributing manifold 26 which, as illustrated, comprises two semi-circular branches disposed about the bases of the radially disposed cylinders 11. Each of the intake pipes 24 is provided with a fuel discharge valve or nozzle 28 having its inlet side connected to the

5 fuel distributing manifold through a conduit 30. The fuel pressure communicated from the manifold 26 through conduits 30 to each discharge valve, urges each valve in an opening direction against a suitable spring or other balancing force. If the engine were always to remain in a substantially constant attitude, the spring biasing force for urging each of the valves in a closing direction could be adjusted to compensate for the difference in fuel pressure at each valve resulting from their difference in elevation. That is, with the engine remaining in a substantially constant attitude each valve 28 may be adjusted such that fuel is always discharged at the same rate into each of the intake pipes 24. Upon an increase or a decrease in the amount of fuel supplied to the manifold 26, each valve 28 will open or close to discharge fuel at a corresponding larger or smaller rate into the associated intake pipe.

20 With such an arrangement and with the engine maintained in a constant attitude, fuel is continuously discharged into each of the intake pipes at equal rates, the fuel being picked up by the air supply to each intake pipe and taken into the associated cylinders on their intake strokes. However, in operation, particularly in an aircraft engine installation, the relative elevation of the various fuel discharge valves will be continuously changing, and therefore, it is essential that such changes in relative elevation of the various valves have no effect or have the same effect on each valve in order to maintain the proper division of fuel flow through the valves.

35 To this end each fuel valve and the entire fuel system is designed so that fuel is admitted to both sides of the valve operating means in such a manner that the differential fuel pressure acting on each valve operating means is the same regardless of the relative elevation of these valves. With such a system the fuel discharge valves may be adjusted to properly divide the fuel flow regardless of the attitude of the engine.

40 Referring particularly to Figure 3, each valve 28 comprises a housing of two halves 32 and 34 between which a diaphragm 36 is supported. A movable valve member 38 is secured to the diaphragm 36 by a nut 40 and is slidably received within an annular valve guide 42. The valve guide 42 is threaded within the housing part 32 and clamps a nozzle member 44 thereto. A conventional spiral type nozzle plug 46 is secured within the nozzle 44 and is provided with a plurality of helically disposed grooves 48 about its periphery. The housing part 32 has an inlet opening 50 for the conduit 30, whereby fuel is admitted therefrom to the interior of the housing and against the valve side of the diaphragm 36.

The annular valve guide 42 is provided with one or more circumferentially spaced openings 52 and the valve member has a tapered end 54 co-operating therewith. For clarity this taper has been greatly magnified in the drawing. With this construction upon axial movement of the valve member 38, the junction 55 of its tapered end 54 with the remainder of the valve member moves across the openings 52 to control the extent to which the valve is open.

The valve housing part 34 is provided with an adjusting sleeve 56 threaded therein and an axially disposed adjusting screw 58 is threaded through one end of said sleeve. The screw 58 is provided with a head end 60 having a helical groove 62 about its periphery for receiving one end of a helically coiled spring 64. The other end of the spring 64 engages the nut 40 to urge the valve member 38 in a closing direction against the fuel pressure acting on the valve side of the diaphragm 36. Upon an increase in the fuel supplied to the fuel manifold 26, there will be an increase in the fuel pressure therein and at the inlet side of each of the valves, whereby this increased fuel pressure acts against the valve side of each valve operating diaphragm 36 to effect a further opening at each of the valves to maintain a proper division of the fuel flow. Any adjustment of the screw 58 relative to the sleeve 56 threads the helical groove 62 of the head 60 along the spring, thereby controlling the length and stiffness of the spring. Also, adjustment of the sleeve 56 determines the fuel pressure at which the valve member 38 begins to open. In order that the sleeve 56 may be adjusted without disturbing the adjustment of the spring 64, the threads on the exterior of the adjusting sleeve 56 may be right handed and its internal threads cooperating with the screw 58 may be left handed, but of the same pitch. A lock nut 66 and a cap 68 are threaded about the sleeve 56 as illustrated.

In addition to the action of the springs 64, each of the valves 38 is also urged in a closing direction by a fuel pressure admitted to the housing portion 34 and against the rear side of the diaphragm 36 through an inlet opening 70. The housing portion of each valve 34 is also provided with an outlet opening 72, and conduits 74 interconnect the exit opening 72 of one valve housing with the inlet opening of another valve housing to serially connect the chambers at the rear sides of the diaphragms 36. As illustrated in Figure 1, the housing parts 34 of the fuel discharge valves for cylinders on the one side of the engine are serially connected together, and similarly, the valve housing parts 34 associated with the cylinders on the other side of the engine are serially connected together. Also, the lower ends of the fuel manifold 26 are connected to the inlet openings of the valve housing portions 34 for the lower end cylinders of each series through restricted orifices 76 and conduits 78. The outlet openings 72 of the valve housing portions 34 for the upper end cylinders of each series are connected through conduits 80 to a valve 82 discharging into the carburetor adapter. The valve 82 is a common type valve which is spring biased toward closed position and is urged toward open position in response to the fuel pressure supplied thereto. The valve 82 is designed to maintain a small back pressure in order to insure that the conduits 74, 78 and 80 and housings 34 remain full of fuel. Because of the small size of the restricted orifices 76, the magnitude and the range of the back pressure maintained

by the valve 82 is much smaller than the magnitude and the range of the fuel pressure within the manifold 26. For example, the fuel discharge pressure at each discharge valve may vary from nine to eleven pounds per square inch between their closed and full open positions, while the back pressure maintained by the valve 82 varies from one to two pounds per square inch. The orifices 76 are designed such that the flow through the valve 82 is quite small; for example, a fuel flow through the valve 82 amounting to but one percent of the total fuel flow has been found to be satisfactory.

With this system each valve assumes a position in which the fuel pressure on the valve side of the diaphragm 36 balances the force of the spring 64 and the fuel pressure on the other side of the diaphragm. Upon an increase or a decrease in the amount of fuel supplied to the fuel distributing manifold 26 there will be a similar opening or closing adjustment of each fuel discharge valve to maintain a proper division of fuel flow. Also, the fuel pressure on the valve side of any two diaphragms 36 differs only by an amount dependent on the difference in the fuel head at each diaphragm, which depends only on the difference in elevation of the two diaphragms. Similarly, the difference in the fuel pressure on the rear side of any two diaphragms 36 differs only by an amount dependent on the difference in the fuel head at each diaphragm, which difference also depends only on the difference in elevation of the two diaphragms. That is, if any one diaphragm 36 is at a higher elevation than a second diaphragm, the fuel pressure on both sides of the one diaphragm will be greater than the corresponding fuel pressures on the two sides of the second diaphragm by an amount equal to the pressure resulting from a fuel head corresponding to their difference in elevation. In other words, the fuel pressure differential on each diaphragm 36 is the same regardless of their relative elevation and therefore the extent to which each valve opening 52 is uncovered is always the same and the fuel flow through each valve is substantially the same. Actually, although each valve opening 52 is uncovered to the same extent, the pressure differential across these openings will be slightly larger for the lower valves because of the larger static fuel head on their inlet sides. However, this latter variation in pressure differential has substantially no effect on the relative magnitude of the fuel flow through each valve, particularly as compared to the effect on fuel flow which a corresponding variation in pressure differential across the diaphragms 36 would have because of the resulting variation in the extent to which each valve opening 52 would be uncovered. In fact, each valve 28 obviously may be so designed that the fuel pressure differential between its inlet and outlet sides is such at each valve opening that the flow through the valve depends primarily only on the extent to which the valve opening 52 is uncovered.

While we have described our invention in detail in its present preferred embodiment, it will be obvious to those skilled in the art, after understanding our invention, that various changes and modifications may be made therein without departing from the spirit or scope thereof. We aim in the appended claims to cover all such modifications and changes.

We claim as our invention:

1. A fluid distributing system comprising a

plurality of valve housings, each of said housings having a movable member dividing said housing into first and second chambers, each of said housings also having a fluid discharge opening communicating with said first chamber and having a valve connected to the associated movable member for controlling the associated discharge opening; a fluid manifold; first passageways connecting said manifold with each of said first chambers; means for supplying a fluid under pressure to said manifold for distribution therefrom through said passageways, through the first chambers and thence through the discharge openings of said chambers, the fluid pressure in each of said first chambers urging the associated movable member in a direction for opening its valve; means providing a source of fluid pressure less than the pressure of the fluid supplied to said manifold; and second passageways connecting said source of fluid pressure with each of said second chambers, the fluid pressure in each of said second chambers urging the associated movable member in a direction for closing its valve.

2. A fluid distributing system comprising a plurality of valve housings, each of said housings having a movable member dividing said housing into first and second chambers, each of said housings also having a fluid discharge opening communicating with its first chamber and having a valve connected to its associated movable member for controlling its associated discharge opening; a fluid manifold; first passageways connecting said manifold with each of said first chambers; means for supplying a fluid under pressure to said manifold for distribution therefrom simultaneously through said passageways and thence through their respective first chambers and the discharge openings of said first chambers, the fluid pressure in each of said first chambers urging the associated movable member in a direction for opening its valve; means providing a source of fluid pressure less than the pressure of the fluid supplied to said first manifold; and interconnected passageways connecting said source of lesser fluid pressure with each of said second chambers, the fluid pressure in each of said second chambers urging its associated movable member in a direction for closing its valve.

3. A fluid distributing system comprising a plurality of valve housings, each of said housings having a movable member dividing said housing into first and second chambers, each of said housings also having a discharge opening communicating with its first chamber; a fluid manifold; first passageways connecting said manifold with each of said first chambers; means for supplying a fluid under pressure to said manifold for distribution therefrom simultaneously through said passageways and thence through their respective first chambers and the discharge openings of said first chambers; means providing a source of fluid pressure less than the pressure of the fluid supplied to said first manifold; second passageways for continuously connecting said source of lesser fluid pressure with each of said second chambers during operation of said system; and a valve connected to each of said movable members for controlling its associated discharge opening for providing equal simultaneous rates of fluid discharge through said discharge openings, each of said movable members being urged in a direction for opening its valve by the fluid pressure in its first chamber and

being urged in the opposite direction by the fluid pressure in its second chamber.

4. A fluid distributing system as recited in claim 3 and including springs for urging each of said movable members in a valve closing direction.

5. A fluid distributing system comprising a plurality of valve housings, each of said housings having a movable member dividing said housing into first and second chambers and providing an imperforate wall between said chambers, each of said housings also having a discharge opening communicating with its first chamber; a fluid manifold; open passageways connecting said manifold with each of said first chambers; means for supplying a fluid under pressure to said manifold for distribution therefrom simultaneously through said passageways and thence through their respective first chambers and the discharge openings of said first chambers; means providing a source of fluid pressure less than the pressure of the fluid supplied to said first manifold; second passageways for continuously connecting said source of lesser fluid pressure with each of said second chambers during operation of said system; and a valve connected to each of said movable members for controlling its associated discharge opening for providing equal simultaneous rates of fluid discharge through said discharge openings, each of said movable members being urged in a direction for opening its valve by the fluid pressure in its first chamber and being urged in the opposite direction by the fluid pressure in its second chamber.

6. A fluid distributing system comprising a plurality of valve housings, each of said housings having a movable member dividing said housing into first and second chambers, each of said housings also having a fluid discharge opening communicating with said first chamber and having a valve connected to its associated movable member for controlling its associated discharge opening; a fluid manifold; first passageways connecting said manifold with each of said first chambers; means for supplying a fluid under pressure to said manifold for distribution therefrom simultaneously through said passageways and thence through their respective first chambers and the discharge openings of said first chambers, the fluid pressure in each of said first chambers urging the associated movable member in a direction for opening its valve; means providing a source of fluid pressure less than the pressure of the fluid supplied to said first manifold; and passageways serially connecting said second chambers to said source of lesser fluid pressure for fluid flow through said second chambers, the fluid pressure in each of said second chambers urging its associated movable member in a direction for closing its valve.
